United States Patent Office.

WILLIAM LONG, OF WEST TROY, AND JAMES GARAND, OF TROY,
NEW YORK.

Letters Patent No. 93,457, dated August 10, 1869.

IMPROVEMENT IN MAKING BUNGS.

The Schedule referred to in these Letters Patent and making part of the same

To all whom it may concern:

Be it known that we, WILLIAM LONG, of West Troy, county of Albany, and JAMES GARAND, of Troy, Rensselaer county, State of New York, have invented certain new and useful Improvements in the Mode of Constructing Bungs for Barrels and similar wooden vessels; and we do hereby declare that the following is a full, clear, and exact description thereof, reference being had to the accompanying drawings, making a part of this specification, in which—

Figure 1 represents a perspective view of the stopper of said bung.

Figure 2 represents a perspective view of the bushing.

Figure 3 is a cross-section of the bung through the bilge of the vessel.

Figure 4 is a vertical view of the same through red line in fig. 3.

Many devices, other than the common wooden bung, have been used to close and stop, perfectly, barrels and other similar wooden vessels. Among them are those classes of metal bungs which have their bushings secured to and in the stave of the vessel, by means of bolts or rivets, or by clinching on the under side, or by screwing them into the holes of the staves; but all these have some defect or disadvantage attending them. Those secured by bolts or rivets can only be attached securely with great difficulty and care; while those secured by clinching are not only to a degree weak, but cannot be reinserted or used a second time; and those secured by screwing into the stave of the vessel cannot have their flanges made to bear on all portions of the vessel, on account of the form of the vessel at its bilge.

In our invention we present a bung which has none of these objections, while it has all the advantages to be found in the others.

The nature of our invention consists in the use of a metal bushing, which is to be inserted and secured in a hole in the stave, and stopped with a metal stopper. The said bushing consists of a thin metal shell, having its outside plain and slightly tapered, to fit the taper of the hole; it is also provided with a flange, having the line of the lower edge so shaped as will conform to the shape of the vessel at the bilge around the hole, and it is also provided with several projections, (which I term flukes,) placed on the plain sides of the said bush, which, when the bush is driven into its place, will hold the whole in its place. A recess-seat is provided in the inside, near the top, to receive any suitable packing. A screw-thread, having several turns, commencing at the packing-seat, is also provided to receive the screw-thread cut on the stopper.

The said stopper consists of a metal piece, with a short screw terminating at a flange, which, when the stopper is secured into the bushing, sets upon the packing on the recess-seat of the bush, and effectually closes the same.

The whole device is not only comparatively inexpensive, but strong and reliable as well as durable, and can be quickly applied to effectually close water-tight any wooden vessel this bung may be adapted to.

To enable others skilled in the art to make and use our invention, we will proceed to describe it, in reference to the accompanying drawings, and the letters of reference marked thereon, the same letters indicating similar parts.

In the drawings, figs. 3 and 4, A represents a section of a stave of a barrel at its bilge.

B, figs. 2, 3, and 4, is the bushing, having a slight taper outside, made plain, as shown in fig. 2, and provided with several flukes, c c. The said flukes commence a little way up from the lower edge of the bushing, (and permit the entrance of the bush in the hole,) and run up within a short distance from the lower side of the flange, and while the flukes are narrow and project but little at their lower ends, form the sides of the bush, while their upper ends are broader and project further. A triangular form given to the said flukes, as shown in fig. 4, is found to be better than most any other.

The object of the said flukes c is to hold the bushing firmly in its place, after it has been driven home in the stave, which the said flukes do by upsetting the fibre of the wood as they are driven down, as shown by red dotted lines in fig. 3, and after being so driven, the elasticity of the fibres of the wood which has been upset and compressed, will close over the upper ends of the said flukes, and effectually prevent the said bushing from being moved or loosened up from its place.

The bush B is also provided with a flange, f, figs. 2 and 3, which flange has not a plain horizontal surface on its lower side, but has its under surface made curving, to suit the curvature of the bilge of the vessel in both directions, which peculiar form of the under surface of the said flange enables it to find a firm bed on every part of the stave immediately under it.

A suitable recess, g, figs. 2 and 4, is provided on the inside of the bushing B, which is sunk a little below the upper surface of the flange f, which recess is to receive the packing O, which may be made of any suitable material.

A screw-thread, s, having several turns, is cut inside the bush, as shown in figs. 2 and 3, commencing at the recess g, and running down about one-fourth (1/4)

of an inch, more or less, which screw-thread is to receive the screw of the stopper C.

The stopper C is made of metal, and consists of the seat-flange *m* and the screw *n*, which screw, when the stopper is to be used, is inserted and screwed into the screw-threads *s* of the bush, when the seat-flange *m* will be drawn down upon the packing O, fig. 3, placed in the recess *g*, and render the connection perfectly water-tight. Any suitable recess, *v*, may be made in the upper surface of the said stopper, to receive any suitable instrument with which the said stopper C could be screwed in or out of the bush B.

Having described our invention, it is to be understood that we do not claim, as parts of our invention, the recess *g*, nor the screw-thread *s*, formed inside the bush, and immediately below the said recess; neither do we claim the flange *f*, when constructed with a plain horizontal under surface, as all these have been used; neither do we claim as new the stopper C, constructed as described; but it is to be understood that one part of our invention consists in the employment

of the flukes *e*, placed on the outside of the plain surface of the taper bush B, to upset and compress the fibre of the wood, (when the said bush B is driven into its hole,) which, after being driven down, will impinge with their upper lips against the said wood, when its fibre will have resumed somewhat its normal condition; and it is also to be understood that another part of our invention consists of giving to the lower surface of the flange *f*, such a line of form as will conform to the bilge of the vessel in both directions.

What we claim, and desire to secure by Letters Patent, is—

The cast-metal bush B, for bungs, having the flange *f*, recess *g*, screw-thread *s*, and projections *e*, when all the parts are constructed as described, for the purpose specified.

WM. LONG.
JAMES GARAND.
